ANTENNA BASE

Edward Finkel, New York, N.Y., assignor to JFD
Electronics Corporation, Brooklyn, N.Y.

Filed Oct. 28, 1970, Ser. No. 22,927

Term of patent 14 years

Int. Cl. D14—03

U.S. Cl. D26—14

FIG. 1.

FIG. 2.

FIG. 3.

FIG. 4.

FIG. 1 is a perspective view of an antenna base showing my new design;

FIG. 2 is a side elevational view of the antenna base of FIG. 1 showing my new design;

FIG. 3 is a front elevational view of the antenna base of FIG. 1 showing my new design; and

FIG. 4 is a top view of the antenna base of FIG. 1 showing my new design.

The undisclosed rear portion of the antenna base is unornamented.

I claim:

The ornamental design for an antenna base, as shown and described.
